UNITED STATES PATENT OFFICE.

JAMES W. BRUBAKER, OF TRACY, IOWA.

WAGON END-GATE.

SPECIFICATION forming part of Letters Patent No. 630,651, dated August 8, 1899.

Application filed June 13, 1899. Serial No. 720,338. (No model.)

To all whom it may concern:

Be it known that I, JAMES W. BRUBAKER, a citizen of the United States, residing at Tracy, in the county of Marion and State of Iowa, have invented a new and useful Wagon End-Gate, of which the following is a specification.

My object is to provide an improved end-gate for farm-wagons that is adapted to be detachably connected with a wagon-box and securely locked in a closed position to the side-boards, as required to prevent the side-boards from spreading, and hinged to the lower portions of detachable standards to be turned backward and downward and retained in a fixed position to be used as a shoveling-board and to be detachably connected with standards adapted to be slidingly connected with the inside faces of the end portions of the side-boards, so that the gate and standards can be locked together and handled jointly to advantage in packing and shipping.

My invention consists in the construction, arrangement, and combination of parts as hereinafter set forth, pointed out in my claims, and illustrated in the accompanying drawings, in which—

Figure 1 is a perspective view showing the detachable standards connected with the side-boards and the gate in position as required for use as a shoveling-board. Fig. 2 is a rear view of the box, showing the end-gate, standards, and side-boards locked together in a closed position, as required to retain small grain and other products filled into the box in bulk. Fig. 3 is an enlarged view of a bolt, and Fig. 4 is a sectional detail view showing how the bolt is applied for locking the standards to the inside faces of the rear ends of the side-boards. Fig. 5 is a detail view showing how the end-gate is detachably hinged to the inside faces and lower ends of the standards.

The letters A and A² designate the parallel side-boards, that may vary in width as desired and upon which auxiliary side-boards may be placed as required to enlarge the box.

A³ is a cross-bar fixed to the bottom of the rear end of the box.

B and B² are mating standards provided with tongues c on their outer edges, adapting

them to be slidingly connected with the inside faces and rear end portions of the parallel side-boards, that have fixed cleats c' and c'', 55 between which the tongue c fits and moves.

In the top portions of the front faces of the standards B and B² are grooves d, adapted to admit the ends of locking-bolts d', extended through bores in the sides of the box, as 60 clearly shown in Fig. 4 and as required to lock the standards to the side-boards. Mating metal plates f are fixed to the inside faces and upper end portions of the standards and provided with openings f' in their rearwardly-projecting ends to admit irons fixed to the end-gate. Metal bearings g, fixed in cavities in the inside faces and lower ends of the standards, serve as parts of hinges for detachably connecting the end-gate with the stand- 70 ards.

H is an end-gate provided with fixed wings H², that extend inward. Irons k are fixed to the outside face of the gate to engage the slotted projecting ends of the metal plates f, 75 fixed to the standards to prevent vertical motion of the gate relative to the standards and the floor of the box as required to maintain a tight joint between the end-gate and the bottom of the box. Irons m, terminating in 80 journals that have enlargements m' at their free ends, are fitted to enter the fixed bearings g, as shown in Fig. 5, as required to detachably hinge the gate to the standards. Mating rods r, having hooks r' at their lower ends, are 85 pivotally connected with the projecting ends of the plates f, fixed to the standards in such a manner that the rods can be placed in crossed position, as shown in Fig. 2, to overlie the fixed irons k on the gate and to be 90 jointly clasped to the lower portion of the gate by means of a clasp s, fixed to the lower central part of the gate as required to detachably connect the gate with the standards, so they can be handled jointly; and when the 95 gate and standards are thus connected with the side-boards of the box all the parts can be readily detachably fastened together by turning the bent ends of the bolt d' into the grooves d in the standards and tightening the 100 nuts d'' on the outer screw-threaded ends of the bolts, and the gate securely locked in a closed position.

To adjust the gate H as required for use as

a shoveling-board, I detach the rods *r* from the clasp *s*, turn the gate outward and downward into position as shown in Fig. 1, and connect the hooks on their free ends with the 5 free end portions of the irons *k*, fixed to the upper and out side of the gate.

Having thus described all the operative parts and their functions, the practical operation and utility of my invention will be readily understood by persons familiar with the art to which it pertains; and

What I therefore claim as new, and desire to secure by Letters Patent therefor, is—

1. In a wagon end-gate, standards adapted 15 to be slidingly connected with the side-boards of a wagon-box and provided with grooves in the top portions of their rear faces, bolts pivotally connected with the side-boards and bent at their inner ends to enter the grooves 20 in the standards, an end-gate and means for detachably fastening the end-gate to the standards for the purposes stated.

2. In a wagon end-gate, standards adapted to be slidingly connected with side-boards of 25 a wagon-box, means for detachably fastening the standards to the side-board, an end-gate, means for detachably hinging the end-gate to the standards, rods hinged to the upper portions 30 of the standards and provided with hooks on their lower ends and irons fixed to the upper portions of the end-gate to be engaged by said hooks, arranged and combined to operate in the manner set forth for the purposes stated.

3. The standards *B* and *B*² having at their 35 upper end portions grooves *d* and fixed plates *f* provided with slots in their projecting ends, and fixed bearings *g* at their lower end portions, the gate *H* having fixed irons *k* to engage the plates *f* and fixed journals *m* to engage the bearings *g* and means for detachably fastening the irons *k* to the plates *f*, for 40 the purposes stated.

4. The standards *B* and *B*² having at their upper end portions grooves *d* and fixed plates 45 *f* provided with slots in their projecting ends, and fixed bearings *g* at their lower end portions, the gate *H* having fixed irons *k* to engage the plates *f* and fixed journals *m* to engage the bearings *g* and means for detachably fastening the irons *k* to the plates *f*, the rods *r* pivotally connected with the plates *f* and provided with hooks at their free ends and a clasp *s* fixed to the end-gate, all arranged and combined to operate in the manner set forth for the purposes stated. 55

5. A wagon end-gate comprising standards having tongues extending vertically on their outside faces, grooves in the upper end portions of their rear faces, metal plates, having 60 slots in their rear ends, fixed to their inside faces and upper end portions, journal-bearings in their lower end portions and inside faces, a gate having wings at its parallel edges, fixed irons at its top portions to engage the slotted plates on the standards and fixed journals to engage the journal-bearings in the standards, rods pivotally connected with the fixed slotted plates on the standards and provided with hooks on their free ends 70 to engage the fixed irons on the top portion of the gate when the gate is in the position of a shoveling-board, a clasp fixed to the lower portion and center of the gate to engage the rods when the gate is in a closed position and bolts fitted in bores in the sides of a wagon-box and provided with bent ends to enter the grooves in the standards and nuts on the outer ends of the bolts, all arranged and combined to operate in the manner set 75 forth for the purposes stated.

JAMES W. BRUBAKER.
